UNITED STATES PATENT OFFICE.

FRANCIS M. NIXON, OF LENA, ILLINOIS, ASSIGNOR OF ONE-HALF OF HIS
RIGHT TO GEORGE BREON, OF SAME PLACE.

IMPROVEMENT IN GATES.

Specification forming part of Letters Patent No. **222,561**, dated December 9, 1879; application filed
September 26, 1879.

To all whom it may concern:

Be it known that I, F. M. NIXON, of Lena, in the county of Stephenson, and in the State of Illinois, have invented certain new and useful Improvements in Gates; and I do hereby declare that the following is a full, clear, and exact description thereof, reference being had to the accompanying drawings, and to the letters of reference marked thereon, making a part of this specification.

The nature of my invention consists in the construction of devices for operating a gate, as will be hereinafter more fully set forth.

In the annexed drawings, Figure 1 is a perspective view of my gate. Fig. 2 is a side elevation of the same.

A represents an upright post, to which is hinged a bar, B, of about the same height as the gate.

To the hinged bar B, at top and bottom, are fastened two converging arms, C C, forming a triangular frame.

a a are two slides, fastened one on the bar B and the other at the junction of the arms c c, and upon these slides the gate D can move backward and forward for a suitable distance, and then swing, with the frame B C, on the hinges b b.

To the post A, a suitable distance above the gate, is pivoted a lever, L, which extends on both sides of the gate, and has at each end a handle, H, suspended from it.

To the inner end of the gate is secured a cord, or its equivalent, d, which is passed through a swivel-pulley, e, on the inner slide,

a, and then connects with one arm of the lever L. A similar cord, d', is attached to the other arm of said lever, and passes down through a swivel-pulley, e', on the post A, and then connects with the lower end of the latch F. This latch is substantially of the form shown in Fig. 2, pivoted at i to the gate, and having its lower end curved upward, with the cord d' attached to said curved end. Before the cord d' reaches the latch it passes through a swivel-pulley, e², on the gate.

By pulling down on that end of the lever L to which the cord d is attached, the other end rises, and the cord d' first raises the latch F from its pin x in the post P and then moves the gate on the slides a backward for a certain distance, and if the movement of the lever is continued the gate swings open. By pulling on the other end of the lever L the gate closes in reverse manner.

Having thus fully described my invention, what I claim as new, and desire to secure by Letters Patent, is—

In combination with the hinged frame B C and sliding gate D, the lever L, cords d d', pulleys e e' e², and latch F, all constructed and arranged to operate substantially as and for the purposes herein set forth.

In testimony that I claim the foregoing I have hereunto set my hand this 20th day of August, 1879.

FRANCIS M. NIXON.
